(57) **CLAIM**

The ornamental design for a piano, as shown and described.

DESCRIPTION

FIG. 1 is a front, top perspective view of a piano, showing my new design;

FIG. 2 is a rear, bottom perspective view thereof;

FIG. 3 is a rear, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a partial enlarged view of FIG. 1; and,

FIG. 11 is a front, top perspective view of the piano in a second state.

The dashed broken lines in the figures are for the purposes of illustrating portions of the piano, which form no part of the claimed design.

The dash-dot-dash broken lines are for notating enlarged views, which form no part of the claimed design.
